CLAIM

The ornamental design for an intranasal drug delivery device, as shown and described.

DESCRIPTION

FIG. 1 is a top-side perspective view of an intranasal drug delivery device showing our new design;

FIG. 2 is a right side view of the intranasal drug delivery device of FIG. 1;

FIG. 3 is a left side view of the intranasal drug delivery device of FIG. 1;

FIG. 4 is a front plan view of the intranasal drug delivery device of FIG. 1;

FIG. 5 is a rear plan view of the intranasal drug delivery device of FIG. 1;

FIG. 6 is a top plan view of the intranasal drug delivery device of FIG. 1; and,

FIG. 7 is a bottom plan view of the intranasal drug delivery device of FIG. 1.

The broken lines in the drawings depict portions of the intranasal drug delivery device that form no part of the claimed design.
